(57) **CLAIM**

The ornamental design for a shoe insole, as shown and described.

DESCRIPTION

FIG. 1 is a front perspective view of a shoe insole showing my new design;

FIG. 2 is a top view thereof; and,

FIG. 3 is a rear perspective view thereof.

The unshaded area and broken line circles form no part of the claimed design.

1 Claim, 3 Drawing Sheets

FIG. 1

FIG. 2

FIG. 3
